UNITED STATES PATENT OFFICE.

CHARLES S. BURTON, OF OAK PARK, ILLINOIS.

FUEL-FEEDING DEVICE FOR INTERNAL-COMBUSTION ENGINES.

1,296,363.

Specification of Letters Patent. Patented Mar. 4, 1919.

Application filed July 9, 1917. Serial No. 179,579.

To all whom it may concern:

Be it known that I, CHARLES S. BURTON, a citizen of the United States, residing at Oak Park, in the county of Cook and State of Illinois, have invented new and useful Improvements in Fuel-Feeding Devices for Internal-Combustion Engines, of which the following is a specification, reference being had to the accompanying drawings, forming a part thereof.

The purpose of this invention is to provide an improved structure of the character commonly called a vacuum feed device, for supplying liquid fuel to an internal combustion engine. It consists in the elements and features of construction shown and described as indicated in the claims.

In the drawings;—

Figure 1 shows a side elevation of a portion of an engine equipped with this invention, the portion of the engine illustrated comprising the manifold and intake tube.

Fig. 2 is an axial section of the air intake tube and of the liquid fuel supply device connected with the float chamber which is shown in elevation.

Fig. 3 is a section at the line, 3—3, on Fig. 2.

Fig. 4 is a plan view of the slotted flange at the line, 4—4, on Fig. 2.

In the drawings 1 represents the intake manifold, 2, the intake leading thereto, 3 the Venturi tube forming a portion of the air intake, 4, the customary float chamber or level-controlling chamber with the fuel nozzle leading from the float chamber and discharging within the Venturi tube. 5 is a main low level fuel supply tank from which a tube, 6, leads to a chamber, 7, in which a vacuous condition is to be produced for causing the liquid fuel to be lifted from the low level tank, 5. 8 is a supplemental reservoir into which the chamber, 7, discharges, and from which the liquid fuel is supplied by gravity to the float chamber, 4, of the carburetor. 9 is a tube leading from the top of the chamber, 7, into and opening within the Venturi tube, 3, within the low pressure or high suction area of said Venturi tube which is indicated by dotted lines at x. Said tube, 9, opens in the chamber, 7, through a restricted port, 9a, which is designed to be continuously open, being unprovided with valve or the like for closing it. The chamber, 7, has an atmosphere port, 10, which is large relatively to the restricted

port, 9a, and which is controlled by a valve, 11, carried at the upper end of a stem, 12, which is guided at its lower end by a spider or the like, 13, over the port, 14, by which 60 the chamber, 7, discharges into the chamber, 8, the discharge being free notwithstanding said stem which obstructs the passage to a negligible extent. 15 is a valve by which the liquid is discharged by gravity from the 65 chamber, 7, into the chamber, 8. 18 is a float mounted for sliding on the valve stem, 12, between two stops, 16 and 16a, thereon. The mouth of the air inlet port, 10, is controlled at its upper end by a woven wire or 70 perforated metal screen, secured by a flanged nut, 19, the screen serving to limit the opening movement of the valve. The boss, 17, through which the air inlet port, 10, is formed, is provided with a depending flange 75 or skirt, 20, whose lower edge is serrated or furnished with a multiplicity of slits, 20a. 21 is an annular upwardly-open pan or cup forming a trap chamber supported from the cap plate, 8a, of the two chambers, 7 and 8, 80 (the chamber, 7, being formed depending into the chamber, 8) said annular pan or trap chamber being of such depth and so positioned that the lower serrated or slotted edge of the flange, 20, depends into said 85 pan around the inner circumferential flange wall thereof. Said annular pan or trap chamber extends under the intake or discharge mouth of the tube, 6, which delivers the liquid from the low level tank into said 90 chamber, 7, whereby said pan or trap chamber is filled with the first discharge of liquid into said chamber and is re-filled at the commencement of each filling action of the device when it has to any extent been drained 95 or partly emptied during the discharge of the contents of the chamber, 7, into the chamber, 8.

The capacity of the device described for serving its purpose of lifting the liquid fuel 100 from a low level tank to a supplemental reservoir at a higher level from which it may be supplied to the engine by gravity, is due to the location of the mouth of the suction tube within the low pressure or high 105 suction area of the Venturi tube, 3. It is known that an air current flowing through a tube of the character commonly called a Venturi tube such as shown in the drawings, tends to produce an area of reduced 110 pressure at a short distance inward from the throat or most restricted point of the

- tube, said area of reduced pressure being, of course, substantially equally distant from all sides of the tube, that is, substantially concentric within the tube. It is known 5 that the degree of vacuum existing in this low pressure space or area increases with the rate of flow of the air through the tube, so that a very rapid air flow will produce an almost perfect vacuum at this low pressure area, the increasing rate of air flow causing the low pressure area to be elongated somewhat after the form of a flame blown by an air current, the degree of vacuum diminishing in the extended portion, but the 10 area of highest vacuum remaining always substantially at the same distance from the point of greatest restriction of the Venturi, and substantially as shown by dotted line, x , in the drawing.
- 15 20 It is well understood that a vacuum fuel feed device of any of the types which have hitherto been in use,—that is, one in which the fuel is lifted from a low level by the suction of the engine, is subject to the defect 25 that when the engine is running with wide open throttle and doing its heaviest work, and consequently requiring the largest amount of fuel to maintain the explosive mixture of the most effective proportions, the direct 30 suction of the engine operating in the intake manifold or in the intake passage thereto is the lowest, and an automobile engine doing heavy work in climbing a steep grade, especially in high altitudes where the atmospheric pressure is low, is frequently unable 35 to keep itself supplied with fuel because the vacuum is inadequate to lift the fuel from the tank to the height of the carburetor, and in long stretches of such service the reserve 40 of fuel accumulated in the reserve reservoir will become exhausted. On the other hand, as above indicated in the description of the characteristics of the Venturi tube with the wide open throttle, and consequent rapid 45 inflow of air through the Venturi tube, the vacuum existing at the low pressure area, x , of the Venturi tube is increased by the freedom of the entrance of the air, causing large volume to move through the Venturi 50 tube, which results in a relatively high velocity through the restricted Venturi throat. That is to say, other things being equal, the vacuum at the particular point referred to as the low-pressure area of the 55 Venturi tube, increases with the degree of opening of the throttle valve. It results that at the time when the direct suction of the engine is at its lowest, the throttle now being wide open, the suction or vacuum at 60 the low pressure area of the Venturi tube gains from that same cause. On the other hand, when the throttle valve is closed or nearly closed, the suction, with the engine at any given speed, is greatest and will serve 65 to produce the suction for lifting the fuel from the low tank to the elevated supplemental reservoir, as well as for drawing it from the nozzle.
- The structure illustrated takes advantage of these peculiar relations of suction or 70 vacuum and air inflow, and thereby insures at all times an adequate suction to keep the elevated reservoir supplied from the low tank by the suction of the engine, said suction operating either directly, as when 75 the throttle valve is closed, or through the effect of the rapid air inflow into the Venturi tube when the throttle is wide open.
- The rise and fall of the float in the chamber, 7, opening the air inlet valve, 11, when 80 the chamber, 7, has become filled to a pre-determined height, and closing that valve when the liquid level falls, causing alternation of the domination of the suction operating through the restricted suction port, 9^a, 85 and of the atmospheric pressure operating through the larger valve-controlled port, 10, causes the liquid lifted by suction to first fill the chamber, 7, and then discharge into the chamber, 8. Any of the other well 90 known methods of effecting alternation of the domination of the atmospheric pressure and suction in the chamber, 7, for the same purpose may be employed. No claim is here made with respect to any particular method 95 for producing this alternation. It is true, however, that when the method of producing the alternation which is here shown is employed,—that is to say, having a valveless restricted suction aperture and a larger 100 valveless air port, the amount of air that is drawn into the manifold when the air valve is open, tending during the interval of emptying of the chamber, 7, to thin the mixture supplied to the engine, operates somewhat to 105 prevent that uniformity in the quality of the mixture which is necessary to maximum economy in respect to fuel consumption. This defect may be obviated to a large extent by the expedient of providing a pan or 110 chamber, 21, which becomes filled with a liquid fuel from the liquid supply pipe, 6, a serrated or slotted flange, 20, depending around the atmosphere inlet port, dipping into the liquid in the pan or touching the 115 surface with the points of the serrations, so that the air which is drawn in through the atmosphere inlet port is, so to speak, fretted over the surface of the liquid, or even drawn through it if the flange, 20, depends sufficiently into the liquid to make it necessary for the air to pass through the liquid in order to enter, and the air thus becomes considerably charged with the vapor of the gasoline, preventing the leanness or thinness of 120 the mixture otherwise resulting from the large atmosphere inlet port which is necessary in view of the continuously operating suction through the suction port.
- 125 This result is facilitated, and the degree 120

of enrichment of the incoming air is increased by flaring the flange, 20, to approximately horizontal form and forming the serrations by narrow slits extending in the flared part as illustrated.

5 I claim:

1. In an internal combustion engine, in combination with a Venturi tube air intake, a low level fuel supply tank, a supplemental 10 reservoir which constitutes the source of supply to the engine, a chamber from which the liquid fuel is delivered by gravity into said supplemental reservoir, and a duct from the upper part of said chamber leading to and 15 opening within the Venturi tube at a point therein removed from the wall thereof and relatively near the axis of the tube.

2. In an internal combustion engine, in combination with a Venturi tube air intake, 20 a low level fuel supply tank, a supplemental reservoir which constitutes the source of supply to the engine, a chamber from which the liquid fuel is delivered by gravity into said supplemental reservoir, a duct from the upper 25 part of said chamber leading to and opening within the Venturi tube at a point therein removed from the wall thereof and relatively near the axis of the tube, and

means in said chamber for alternating the domination of atmospheric pressure and suction through said duct. 30

3. In a construction such as set out in claim 2 foregoing, the means for effecting such alternation of domination, consisting of a continuously open suction port and a 35 valved atmosphere port, the latter being large relatively to the former; a float in the chamber operating to open the atmosphere valve by the rise of the float, the atmosphere port having a depending flange, and a trap 40 chamber into which said flange depends positioned for being filled by the inflow of the liquid.

4. In a structure such as set out in claim 3 foregoing, the lower margin of the depending 45 flange being serrated.

5. In a structure such as set out in claim 4 foregoing, the flange being flared to approximately horizontal form and having the serrations formed by narrow slits in the flared 50 part.

In testimony whereof, I have hereunto set my hand at Chicago, Illinois, this 27th day of June, 1917.

CHARLES S. BURTON.
